JUHANA KYLLIÄINEN, OF HELSINKI, FINLAND.

REVERSING-GEAR FOR INTERNAL-COMBUSTION ENGINES.

1,202,537.

Specification of Letters Patent.

Patented Oct. 24, 1916.

Original application filed August 31, 1911, Serial No. 647,114. Divided and this application filed October 8, 1912. Serial No. 724,641.

To all whom it may concern:

Be it known that I, JUHANA KYLLIÄINEN, a citizen of Finland, residing at Helsinki, Finland, have invented certain new and useful Improvements in Reversing-Gear for Internal-Combustion Engines, of which the following is a specification.

In accordance with this invention the ignition shaft of the engine is longitudinally movable and is provided with a grooved bushing adapted to hold the shaft in its different positions of longitudinal movement, the shaft being also provided with circuit closer and brushes for causing the 10 sparking at the right time for normal working in either direction and for reversing, the sparking time being controlled by the longitudinal position of the ignition shaft.

In the accompanying drawing: Figure 1 20 is a central vertical sectional view of a grooved bushing for a two-cycle single cylinder motor; Fig. 2 is a diagrammatic end view showing the relations of the parts of the circuit closer; Fig. 3 is a peripheral development of said bushing shown in relation to the circuit closer, also similarly developed; Fig. 4 is a central vertical sectional view of a reversing gear for a two-cycle single cylinder motor; Fig. 5 is a horizontal 30 sectional view of the Fig. 4 along the line C—D; Fig. 6 is a plan of the Fig. 4.

Reference will first be made to Figs. 1 to 3. The ignition-shaft L is adapted for a two cycle engine and is constructed so as to 35 permit it to move along its axis, a bushing Wr (Figs. 1 to 5) provided with four grooves 1, 2, 3 and 4 being fastened on said shaft. The grooves coöperate with respective corresponding circuit closers ko₁, ko₂, ko₃ and ko₄, each situated at a point on one 40 of the tracks 1', 2', 3', 4' of the ignition drum (Ka), which is fastened on the same shaft L as the bushing (Wr). During the rotation of the shaft, a pin t engages in and 45 may be said to move relatively to the groove 1 in the direction indicated by the arrows, and the circuit closer (ko₁) causes the charge to be ignited when said circuit closer touches the brush h at the end of the compression. 50 The distance the bushing moves angularly relatively to the brush during the expansion is shown by pa, during the exhaust by po, and during the compression by pu. As may be seen, these contact-pieces are arranged so 55 that ko₁ ignites at the end of the compres-

sion-stroke ko₂ at the beginning of the compression, or if the direction of rotation is opposite ko₃ ignites, at the beginning of the compression, and ko₄ at the end of the compression-stroke in the same way as ko₁. The 60 grooves 1—4 are connected with each other by means of oblique grooves a, b, c, d, e. If it is desired to effect a rotation in the opposite direction, the ignition shaft with its bushing must be moved so that ko₂ comes 65 under the brush h, which insures ignition at the beginning of the compression. Gases caused by the combustion are compressed and expand again during the following stroke, but the action of the counter-pressure 70 is, of course, greater during the compression than the driving action during the expansion, because of the radiation of heat. As a consequence of this, the speed slackens till the motor finally stops, after a number of 75 strokes, near the end of the compression stroke, and the motor begins to rotate in the opposite direction. As soon as the motor has commenced to run in the opposite direction, the bushing is adjusted so that ignition 80 by means of ko₄ comes into action and an ordinary backward rotation takes place. If, on the other hand, a rotation forward is wanted, the ignition shaft must be moved so that the contact piece ko₃ comes into action, 85 and, as soon as the direction of the rotation is changed, the ignition shaft is moved to bring ko₁ into action.

The bushing Wr is shown by Fig. 1, Fig. 3 giving a view of its periphery. To the 90 engine is fastened a pin, which runs in one of the grooves 1—4, or, when the bushing is moved sidewise through one of the oblique grooves from one main-groove to another. During rotation in the forward direction, 95 the pin t runs in the groove 1 in the direction indicated by the arrows. If the ignition shaft, with its bushing is moved to the left on the drawings, the pin t at the cut-out portion a can be moved, at the moment when the exhaust-stroke ends and the compression-stroke begins, to the groove 2, and an alteration of the direction of the rotation takes place, as already described. During 100 the backward rotation the pin can move to the oblique grooves b and c to the groove 4, and the contact-piece ko₄ comes under the brush, which corresponds to a normal backward rotation. The paths through which the pin and the brush go, owing to the 110

- movement of the bushing and the ignition drum, during the expansion, the exhaust and the compression is shown by pa_1 , po_1 and pu_1 . When the rotation is to be changed from backward to forward, the bushing is pressed to the right on the drawings so that the pin at the cut out portion d moves from the groove 4 to the groove 3 and, the direction of the rotation having changed, through the oblique grooves $b-e$, to the groove l . In this way, the direction can be altered from full speed ahead to full speed backward and from forward to backward.
- 15 The practical arrangement of reversing gear according to the above described principle is shown for a single cylinder two-cycle motor in Figs. 4, 5 and 6, showing the bushing Wr and the circuit closer Ka , both fastened on the shaft 1 which by means of the lever B can be moved vertically. h represents the brush which slides against either of the tracks 1', 2', 3' or 4' and which by means of the lever A can be angularly adjusted so as to cause the point of ignition to be advanced or retarded. The shaft L which holds the bushing Wr and the circuit closer Ka gets the rotary motion from the main shaft by means of a pair of bevel wheels. The pin t which slides in the grooves 1-4 is fastened to the main frame; the brush h is fastened to an open or closed frame which can be angularly adjusted so that the ignition takes place later to slow the engine down before reversing. The shaft L is vertically adjustable, the position of the shaft L and lever B is shown in the Fig. 4 for the forward rotation.
- I claim as my invention:—
- 40 1. In a reversing gear for internal combustion engines, the combination of a support; a brush carried thereon; an ignition shaft provided with four contacts longitudinally and angularly displaced from each other and so disposed thereon angularly

that the two end contacts cause ignition at the end of the compression when the end is running in respective opposite directions, the contacts adjacent to said end contacts being placed so as to cause ignition at the beginning for compression for said respective directions; and means for moving said shaft longitudinally of the brush and the support.

2. In a reversing gear for internal combustion engines, the combination of a support; a pin and a brush carried on said support; an ignition shaft provided with four interconnecting grooves; four contacts on said shafts longitudinally displaced from each other; said pin, brush, contacts and grooves being so relatively displaced that, when the pin engages a groove, the brush is adapted for contact with a corresponding contact; and means for causing relative longitudinal movement between said shaft and brush.

3. In a reversing gear for internal combustion engines, the combination of a support; a pin and a brush carried by said support; an ignition shaft; four contacts longitudinally displaced on said shaft and so disposed thereon angularly that the two end contacts cause ignition at the end of the compression when the end is running in respective opposite directions; a bushing on said shaft and provided with four interconnecting grooves, said brush, pin, grooves and contacts being so spaced that when the pin engages in a groove, the brush is adapted for contact with a corresponding contact; and means for causing relative longitudinal displacement between said brush and shaft.

In testimony whereof I have affixed my signature in presence of two witnesses.

JUHANA KYLLIÄINEN.
